US0D1082445S

(12) **United States Design Patent** (10) **Patent No.:** **US D1,082,445 S**
(45) **Date of Patent:** **** Jul. 8, 2025**

(54) **INSULATED CONTAINER**

(71) Applicant: **EVERICH AND TOMIC
HOUSEWARES CO., LTD.,**
HangZhou (CN)

(72) Inventor: **Huajun Yao**, HangZhou (CN)

(73) Assignee: **EVERICH AND TOMIC
HOUSEWARES CO., LTD.,**
HangZhou (CN)

(**) Term: **15 Years**

(21) Appl. No.: **29/923,057**

(22) Filed: **Dec. 27, 2023**

(30) **Foreign Application Priority Data**

Jun. 27, 2023 (CN) 202330395951.3

(57) **CLAIM**

The ornamental design for an insulated container as shown and described.

DESCRIPTION

FIG. 1 is a front perspective view of an insulated container showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the insulated container that form no part of the claimed design.

1 Claim, 8 Drawing Sheets
